UNITED STATES PATENT OFFICE

JOHN SQUIRES, OF HAGERSTOWN, MARYLAND

METHOD OF MAKING PROPELLER BLADES

Application filed December 9, 1929. Serial No. 412,670.

This invention relates to a method of forming hollow, seamless steel propeller blades.

The main objects of this invention are to provide an improved method of forming a metal propeller blade; to provide a method of forming a propeller blade of superior quality and strength; to provide a method of forming a propeller blade from a disc-shaped blank by subjecting it to a series of drawing, swaging and forming dies; to provide an improved method of making a hollow, metal propeller blade which has a substantially uniform taper to the thickness of its wall; and to provide an improved method by the use of which an exceptionally high-grade propeller blade may be constructed at a relatively low cost.

An illustrative embodiment of this invention is shown in the accompanying drawing, in which:

Fig. 1 is an edge view of the disc-shaped blank from which the propeller blade is made.

Fig. 2 is a plan view of the same.

Fig. 3 is a sectional view showing the first pair of drawing dies after the first draw has been made of the blank.

Fig. 4 is a similar view of the next pair of drawing dies after the next draw of the metal.

Fig. 5 is a similar view of the third pair of drawing dies after drawing the metal.

Fig. 6 is a similar view showing the tapered drawing dies after having drawn the blank to a substantially uniform taper throughout its length.

Fig. 7 is a fragmentary sectional view of the swaging dies after having formed the bead around the open end of the base of the blank.

Fig. 8 is a fragmentary sectional view showing the base bead after having been machined.

Fig. 9 is a thin sectional view showing the tubular blank in position between the forming dies.

Fig. 10 is a similar view of the same after the forming dies have pressed the tubular blank to an airfoil section.

In the embodiment disclosed in the accompanying drawing a disc-shaped blank of steel

11 is placed between a pair of drawing dies 12 and 13 and the dies closed, as shown in Fig. 3 of the drawing, so as to draw out the middle portion of the blank to make it of shallow cup-shape.

The cup-shaped blank is then placed between a second pair of drawing dies 14 and 15, which draw out a smaller portion 16 of the blank, such portion being concentric with respect to the original disc and the cup-shaped blank after the first draw.

The blank is then placed in another set of dies 17 and 18 which draw out a progressively smaller concentric portion 19 of the blank, thus causing the blank to be step-shaped in longitudinal section, as shown in Figs. 4 and 5 of the drawing. This successive drawing of progressively smaller concentric portions is continued until the blank has assumed proper length, at which time it is then subjected to the action of a pair of tapered dies 20 and 21 of circular cross section and having a substantially uniform taper from end to end. These dies form the blank into an elongated uniformly tapered tube 22 as shown in Fig. 6 of the drawing. The base or open end of the tube is then subjected to the action of a pair of swaging dies 23 and 24 which form an outwardly extending annular flange or bead 25 around the open end of the tube 22.

The bead 25 is then machined to form a flange 26 as shown in Fig. 8 of the drawing, by which the finished propeller blade may be mounted in a suitable socket.

The tube 22 is then placed between a pair of forming dies 27 and 28 which have depressions 29 and 30 therein. The depressions 29 and 30 have the same perimetric measurement as the outer circumference of the tube 22 so that the tube will not be stretched during the forming operation. The dies 27 and 28 are then brought together as shown in Fig. 10 of the drawing, thus changing the cross sectional shape of the tube from circular to an airfoil section.

This forming operation is described more in detail in my copending application which bears Serial No. 334,876, filed January 25, 1929.

Although but one specific embodiment has been herein disclosed, it will be understood that numerous details thereof may be altered or omitted without departing from the spirit of this invention, as defined by the following 5 claims.

- I claim:
1. The method of forming a hollow, seamless metal propeller blade which comprises the subjecting of a disc-shaped blank successively to the action of a plurality of pairs of drawing dies, each pair of which draws out a progressively smaller concentric portion of the blank to make it substantially step-shape in longitudinal section, then subjecting the blank to the action of a pair of tapered drawing dies, upsetting a bead around the open end of said blank, and then subjecting the blank to a pair of forming dies for pressing opposite sides of the tapered blank 10 toward each other to secure the desired cross-sectional shape.
  2. The method of forming a hollow, seamless metal propeller blade which comprises the subjecting of a disc-shaped blank successively to the action of a plurality of pairs of drawing dies, each pair of which draws out a progressively smaller concentric portion of the blank to make it substantially 15 step-shape in longitudinal section and having a closed outer end, then subjecting the blank to the action of a pair of tapered drawing dies, and then subjecting the blank to a pair of forming dies for pressing the tapered blank to an airfoil cross-section.
  3. The method of forming a hollow, seamless metal propeller blade which comprises the subjecting of a disc-shaped blank successively to the action of a plurality of pairs of drawing dies, each pair of which draws out a progressively smaller concentric portion of the blank to make an elongated tubular structure of varying diameter and wall thickness having a closed outer end, then subjecting the 20 blank to the action of a pair of tapered drawing dies of circular cross-section, and then subjecting the blank to a pair of forming dies for pressing the tapered tubular blank to an airfoil cross-section.
  4. The method of forming a hollow, seamless propeller blade which includes subjecting a disc-shaped metal blank successively to the action of a plurality of drawing dies whereby to form said blank into an elongated 25 cup shaped member gradually tapering in diameter and wall thickness towards the closed end thereof, and squeezing said member between a pair of dies to form it into blade shape.
  5. The method of forming a hollow, seamless propeller blade which includes subjecting a disc-shaped metal blank successively to the action of a plurality of drawing dies whereby to form said blank into an elongated 30 cup shaped member having a gradually rounded closed end and gradually tapering in diameter and wall thickness towards the closed end thereof, and squeezing said member between a pair of dies to form it into blade shape.
  6. The method of forming a hollow, seamless propeller blade which includes subjecting a disc-shaped metal blank successively to the action of a plurality of drawing dies whereby to form said blank into an elongated 35 cup shaped member having a gradually rounded closed end and gradually tapering in diameter and wall thickness towards the closed end thereof, forming a peripheral flange at the open end thereof, and then squeezing said member between dies to blade formation.
  7. The method of forming a hollow, seamless propeller blade which includes subjecting a disc-shaped metal blank successively to the action of a plurality of drawing dies whereby to form said blank into an elongated 40 cup shaped member having a gradually rounded closed end and gradually tapering in diameter and wall thickness toward the closed end thereof, forming a peripheral flange at the open end thereof, and then squeezing said member between dies to blade formation without circumferentially stretching said walls of said member.

JOHN SQUIRES.
